Primary Examiner — Sheryl Lane*Assistant Examiner* — Leisha Price(74) *Attorney, Agent, or Firm* — MILES & STOCKBRIDGE P.C.; David R. Schaffer(57) **CLAIM**

The ornamental design for a golf cart lift, as shown and described.

DESCRIPTION

FIG. 1 is a front view of the golf cart lift.

FIG. 2 is a top view of the golf cart lift.

FIG. 3 is a bottom view of the golf cart lift.

FIG. 4 is a back view of the golf cart lift.

FIG. 5 is a front perspective view of the golf cart lift;

FIG. 6 is an enlarged left side view of the golf cart lift; and,

FIG. 7 is an enlarged right side view of the golf cart lift.

The broken lines are included for the purpose of illustrating portions of the golf cart lift and form no part of the claimed design.
